ILLUMINABLE DISPLAY SIGN OR SIMILAR ARTICLE

Conrad J. Escalante, 1251 W. Gaylord St.,
Los Alamitos, Calif. 90813

Filed Sept. 28, 1966, Ser. No. 4,070

Term of patent 14 years

(Cl. D1—12)

FIG. 1.

FIG. 2.

FIG. 3.

FIG. 4.

FIGURE 1 is a front elevational view of an illuminable display sign or similar article embodying my new design;

FIGURES 3 and 4 are top and bottom plan views thereof, respectively.

The broken-line representation of advertising matter, supporting structures and brackets is for purposes of illustration only.

I claim:

The ornamental design for an illuminable display sign or similar article, substantially as shown and described.
